DESIGN FOR A COVER FOR SPARE WHEELS AND TIRES OF AUTOMOTIVE VEHICLES

Oscar U. Zerk, Chicago, Ill.

Application April 10, 1936, Serial No. 62,055

Term of patent 7 years

To all whom it may concern:

Be it known that I, Oscar U. Zerk, a citizen of the United States, residing at Chicago, in the county of Cook and State of Illinois, have invented a new, original, and ornamental Design for a Cover for Spare Wheels and Tires of Automotive Vehicles, of which the following is a specification, reference being had to the accompanying drawing, forming a part thereof, in which:

Fig. 1 is a front elevational view of a cover for spare wheels and tires of automotive vehicles showing my invention;

Fig. 2 is a perspective view of the embodiment of Fig. 1 taken from the side thereof.

I claim:

The ornamental design for a cover for spare wheels and tires of automotive vehicles substantially as shown.

OSCAR U. ZERK.
